UNITED STATES PATENT OFFICE.

PETER H. SCHLUETER, OF CHICAGO, ILLINOIS.

COOKING VESSEL.

1,136,277.

Specification of Letters Patent. Patented Apr. 20, 1915.

Application filed April 22, 1914. Serial No. 933,625.

To all whom it may concern:

Be it known that I, PETER H. SCHLUETER, a citizen of the United States, and resident of Chicago, county of Cook, and State of Illinois, have invented certain new and useful Improvements in Cooking Vessels, of which the following is a specification, and which are illustrated in the accompanying drawings, forming a part thereof.

The invention relates to apparatus for cooking candy and the object of the invention is to provide an improved form of cooking apparatus in which the heat required is obtained by the use of steam.

The invention has especial reference to the production of the class of candies known as boiled goods or hard goods, and apparatus for the production of these candies is illustrated in the accompanying drawings, where-

in—
Figure 1 shows the apparatus in side elevation with a detail of one of the parts broken away and represented in section, Fig. 2 is a detail central sectional view of the apparatus, and Fig. 3 is a rear elevation of the same with some of the parts shown in section.

In carrying out the invention the parts of the apparatus are desirably associated upon an integral frame comprising a floor plate, 10, the standards 11, 12 and a pedestal 13. Preferably a diagonal brace, as 14, has its opposite ends bolted to one of the standards 11, 12 and the pedestal 13, whereby each of these standards is connected with the pedestal about mid-way of the height of these parts. A shelf 15 is preferably also provided. As shown this shelf is formed integral with the pedestal 13 adjacent the lower end of the same and extends rearwardly and laterally therefrom.

A tilting kettle 16 having a steam jacket 17 is hung between the standards 11 and 12. For supporting the kettle upon the standards, trunnions, as 18, 19, provided at opposite sides of the kettle are journaled in the standards adjacent the higher ends of the same. The trunnion 19 is desirably made tubular and is rigidly mounted upon the wall 50 of the kettle above the steam jacket 17. A nipple 20 for connection with a steam supply pipe (not shown) extends into the bore of the trunnion 19. To permit the trunnion to rotate about this nipple during the tilting of the kettle, the nipple is swiveled in the trunnion and is packed to provide against leak-

age of the same. As shown, an annular outstanding flange 21 is formed upon the nipple at its inner end and a packing gland 22 surrounds the stem of the nipple and has threaded connection with the wall of the trunnion. A nut 23 applied to the outer end of the nipple 20 serves for compressing a quantity of packing material, as 24, between the inner end of the gland 22 and the flange 21. A pipe 25 extends between the trunnion 19 and the steam jacket 17. The bore of this pipe communicates with the bore of the trunnion and a chamber of the steam jacket 17 for conveying steam to the jacket. 60 If desired, a valve 26 may be mounted in the pipe 25 for controlling the passage of steam therethrough. The trunnion 18 is desirably also made tubular and serves as a bushing for a shaft 27. As shown, this shaft extends through the adjacent wall of the kettle 16 and has its end rotatably seated against a tubular boss 28, which is formed upon the inside wall of the kettle in line with the bore of the trunnion 19. The opening through 65 the boss 28 communicates with the bore of the trunnion 19 and the shaft 27 is made tubular for a portion of its length to permit of the admission of steam into a coil 29 which is carried by the shaft. To prevent leakage 70 of steam between the boss 28 and the adjacent end of the shaft 27, provision is made for packing the joint between these parts. As shown, a flange 30 is formed upon the adjacent end of the shaft and a clamping 75 ring 31 extends over this flange and has threaded engagement with the exterior surface of the boss 28. The coil 29 rotates with the shaft 27 and serves both for stirring and heating the contents of the kettle. A pulley 80 32 is preferably mounted upon the outer end of the shaft 27 for receiving power to turn the same.

A steam discharge pipe 33 extends laterally away from the trunnion 18, at a point 85 between the standard 11 and the adjacent side of the kettle. This discharge pipe is preferably made flexible to permit partial rotation of the trunnion 18 incident to the tilting of the kettle. It may serve both to 90 receive steam which is passed through the coil 29, as also the discharge from the jacket 17. That which has passed through the coil 29 reaches the discharge pipe 33 by transversing the bore, as 34 of a tubular 95 part of the shaft 27 and a lateral opening 35 which is provided in the shaft in line

with the discharge pipe 33. To provide communication between the lateral opening 35 and the discharge pipe 33 at all times irrespective of the rotation of the shaft 27, an annular groove 36 is formed in the wall of the trunnion 18. The discharge from the kettle 17 reaches the pipe 33 through a pipe 37 which has one end connected with the foot of the steam jacket 17 and the other end connected with the trunnion 18 in line with the annular groove 36.

Leakage of steam about the shaft 27 and into the open air through the outer end of the trunnion 18 is prevented by packing the shaft at the point where it leaves the trunnion. As shown, a gland 38 surrounds the shaft 27 and has threaded connection with the outer end of the trunnion 18. Leakage of steam about the shaft 27 and into the kettle 16 is prevented by also packing the shaft at the inner end of the trunnion. As shown, an annular rib, or flange 39, is formed on the shaft 27 adjacent the inner end of the trunnion and a gland 40 surrounds the shaft 27 and has threaded engagement with the trunnion. To permit the assembling of the parts, the shaft 27 is conveniently made in two sections, one section, as 41, being located within the kettle 16 and serving to carry the coil 29 and the other section, as 42, extending through the trunnion 18. These sections are connected by a union 43. If desired a drain cock 44 may be provided in the pipe 37 adjacent the bottom of the kettle.

In some instances it may be desirable to treat the contents of the kettle 16 under vacuum. For this purpose a hood 45 adapted to make sealed engagement with the rim of the kettle 16 is provided. As shown, the rim of the hood 45 and kettle 16 are each reinforced by a ring, as 46 and 47. These rings have a complementary tongue 48 and groove 49, the latter being partially filled with a packing material 50. A plurality of clamps 51, serve for securing the rings 46 and 47 in engagement.

To permit the hood 45 to be conveniently lifted out of engagement with the kettle 16, the hood is carried by a bracket arm 52 which is hingedly connected to the top of the pedestal 13. As shown, the pedestal 13 is bifurcated adjacent its higher end and the bracket arm 52 extends between the arms, as 53, 54 of the pedestal and has trunnions, as 55, 56, which are journaled therein. The bracket arm 52 has an upstanding tubular head 57, the bore of the head being extended laterally through one of the trunnions, as 56. The passage thus formed communicates with the chamber of the hood 45 through a goose neck 58, which extends between the top of the hood and the top of the bracket head 57 and has its opposite ends firmly bolted to these parts.

A condenser 59, and pump 60, serve for exhausting the chamber of the kettle and hood when these parts are in sealed engagement. The pump 60 and the motor 61 for driving the same are conveniently mounted upon the shelf 15. The motor 61 and pump 60 are operatively connected, as by intermeshing gears 62 and 63 mounted on the spindles of the motor and pump, respectively. The condenser 59 is conveniently located directly over the pump 60. A stand-pipe 64 leading out of the lower end of the condenser serves both for connecting the chamber of the condenser with the chamber of the pump and for supporting the condenser. A water supply pipe 65 leads into the top of the condenser 59 and communicates with a spray head 66, which is located within the chamber of the condenser adjacent its higher end. As is usual in devices of this kind a foraminous plate or screen 67 extends across the chamber of the condenser intermediate its ends.

An exhaust pipe 68 has swivel connection between the outer end of the tubular trunnion 56 and the bracket arm 52 and leads therefrom into the side of the condenser 59 above the screen 67. To provide a tight joint between the end of the exhaust pipe 68 and the trunnion 56 while still permitting the rotation of the latter incident to the raising and lowering of the hood 45, the end of the trunnion is formed with a socket 69 for receiving the end of the exhaust pipe and the latter is provided with a circumferential flange or bead 70. A gland 71 which slides upon the exhaust pipe 68 is screwed into the socket 69 and serves for compressing a quantity of packing material 72 against the flange or bead 70.

Sight glasses 73, 74 and a relief valve 75 are desirably mounted in the hood 45. As shown, the hood also carries a thermometer 76 and pressure gage 77, the former having its stem 78 extended downwardly to enter the chamber of the kettle 16, when the hood and kettle are connected. The handle 79 is secured against the front of the hood for lifting the same. Similarly a handle 80 is mounted on the wall of the kettle for tilting the kettle when the hood has been raised. Provision is desirably also made for supporting the hood 45 in horizontal position in event the kettle has been removed from between the standards 11, 12. As shown, a fixed bracket arm 81 extends upwardly and forwardly from the pedestal 13 and a set screw 82 extends vertically through the outer end of the same for engagement with the under side of the tilting bracket arm 52. The coil 29 is preferably so formed that the intermediate turns of the same are of greater diameter than the turns adjacent the ends of the coil. The outline of the coil thus conforms in shape with that of the kettle 16.

When the coil is so formed rigidity is imparted to the intermediate turns of the coil by mounting a spider 83 upon the section 41 of the shaft, the arms, as 84, of the spider 5 being connected with an adjacent part of the coil for supporting the same.

During the operation of the apparatus, the shaft 27 will be rotated. This serves to revolve the coil 29 within the chamber of the 10 kettle for stirring the contents of the kettle and bringing all parts of the coil into intimate contact therewith. Steam supplied through the nipple 20 will pass through the coil 29 and through the jacket 17 of the kettle or through the former alone if the valve 15 26 be closed. Usually the contents of the kettle will be partially cooked while the kettle is open. The hood 45 will then be lowered and the contents of the kettle subjected to any desired degree of vacuum by 20 admitting water to the chamber of the condenser 59 through the water supply pipe 65 and by operating the pump 60. When the cooking operation has been completed, the 25 relief valve 75 will be opened, the clamps 51 loosened and the hood 45 raised. The kettle 16 may then be tilted for emptying the contents of the same upon a slab.

I claim as my invention,—

30 1. In combination, a bowl shaped kettle, a cover adapted to make sealed engagement with the rim of the kettle, said cover being hingedly supported at one side of the kettle, vacuum creating means connected with the 35 cover and means for heating the kettle.

2. In combination, a bowl shaped steam jacketed kettle, a cover adapted to make sealed engagement with the rim of the kettle, said cover being hingedly supported at 40 one side of the kettle, and vacuum creating means connected with the cover.

3. In combination, a tilting bowl shaped kettle, a cover adapted to make sealed engagement with the rim of the kettle when the kettle is upright, the cover being hingedly supported at one side of the kettle, vacuum creating means connected with the cover and means for heating the kettle.

4. In combination, a supporting frame, a kettle mounted therein, a hood, the rims of 50 the hood and kettle being constructed for sealed engagement, a bracket arm supporting the hood and having a tubular trunnion journaled in the frame, vacuum creating means, connection between the vacuum 55 creating means and the bore of the said trunnion including a pipe having swiveled connection with the end of the trunnion, connection between the bore of the trunnion and the chamber of the hood and means for 60 heating the kettle.

5. In combination, a supporting frame, a kettle and a hood each having a trunnion journaled in the supporting frame and the rims of the kettle and hood being constructed 65 for sealed engagement, vacuum creating means connected with the hood and means for heating the kettle.

6. In combination, a kettle and a tilting 70 hood having a trunnion journaled in a fixed support, the rims of the kettle and hood being constructed for sealed engagement, vacuum creating means connected with the hood and means for heating the kettle.

7. In combination, a kettle and a tilting 75 hood having a tubular trunnion journaled in a fixed support, the rims of the kettle and hood being constructed for sealed engagement, connection between the bore of the trunnion and the chamber of the hood, and 80 a vacuum pipe having swiveled connection with the end of the trunnion.

8. In combination, a supporting frame, a tilting kettle having its trunnion journaled in the supporting frame, a cover adapted to 85 make sealed engagement with the rim of the kettle, a bracket arm hingedly mounted in the supporting frame at one side of the kettle and carrying the cover, means for heating the kettle and means for exhausting the 90 chamber of the kettle when sealed by the cover.

PETER H. SCHLUETER.
